CLAIM

I claim the ornamental design for a gaming machine display, as shown and described.

DESCRIPTION

FIG. 1 is a perspective view of a gaming machine display in accordance with the new design.

FIG. 2 is a left side view of the gaming machine display shown in FIG. 1.

FIG. 3 is a right side view of the gaming machine display shown in FIG. 1; and,

FIG. 4 is a top view of the gaming machine display shown in FIG. 1.

The broken line showing of portions of the gaming machine display depicts environment and forms no part of the claim.

1 Claim, 4 Drawing Sheets
